RAILWAY DRAFT RIGGING

Filed Dec. 22, 1927

UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed December 22, 1927. Serial No. 241,744.

This invention relates to improvements in railway draft riggings.

One object of the invention is to provide, in a railway draft rigging, simple and efficient shock absorbing mechanism, having a relatively long compression stroke during buff and shorter stroke during draft.

Another object of the invention is to provide a railway draft rigging, including shock absorbing means operated through the usual coupler, wherein the coupler has relatively long travel, and means is provided for connecting the coupler shank and the shock absorbing mechanism, arranged so that axial alignment of the coupler shank and the shock absorbing means co-operating therewith will be accurately maintained under all conditions of operation.

A further object of the invention is to provide a railway draft rigging having relatively long travel, including the usual coupler and shock absorbing means co-operating therewith, wherein the shock absorbing means is disposed between the usual center sills and contained within a yoke-acting means directly connected to the shank of the coupler, the yoke means being arranged to provide a support for the coupler closely adjacent the coupler head in all operative positions of the mechanism, to prevent tilting of the coupler, thereby assuring proper alignment of the couplers of adjacent cars to be coupled.

Other and further objects of the invention will more clearly appear from the description and claims hereinafter following.

In the drawings, forming a part of this specification, Figure 1 is a longitudinal, vertical, sectional view of a portion of a car showing my improvements in connection therewith, the parts being in the position assumed in the full release of the shock absorbing mechanism. And Figure 2 is a horizontal, longitudinal, sectional view, corresponding substantially to the line 2-2 of Figure 1.

In said drawings, 10-10 indicate the usual center or draft sills, the same being preferably of channel section. The usual angle end sill of the car is designated by 11, and 12 indicates the end wall sheathing. The usual

floor or cover plate for the sills is provided and is designated by 13. A buffer block 14 is suitably secured to the angle end sill 11, and is provided with the usual opening 15 adapted to accommodate the movable parts of the draft mechanism. The end sill is designated by 16 and the same supports the buffer block 14 in the usual manner. The body bolster of the car is indicated by 17 and includes the usual body bolster stop casting 18, which, as shown, is secured to the center sills 10 by rivets.

In carrying out my invention, the center sills 10 are provided with aligned coupler key-receiving openings 19-19 adjacent the forward end thereof. The sills are also provided with top and bottom additional key-receiving openings or slots 20-20 disposed rearwardly of the openings 19. The top and bottom slots 20 are arranged in sets, the sets of the opposite sills being in transverse alignment.

In the improved draft rigging, as shown, is included a standard coupler, indicated broadly by A; a yoke-acting casing B; a front follower C; a coupler key D; two additional keys E-E; a spring follower cap F; a retainer bolt G; and a spring resistance H.

The yoke-acting casing B is disposed between the center sills and is supported at the rear end by the usual carry iron 21, the carry iron being secured to the center sills in any well known manner, the same being illustrated as secured by bolts so as to make the saddle plate detachable. At the forward end, the casing B is supported for sliding movement by the lower transverse member 22 of the buffer block casting 14. The casing B is preferably of rectangular cross-section, having longitudinally disposed spaced vertical side walls 23-23, horizontally disposed spaced top and bottom walls 24-24, and a rear end wall 25. As shown in the drawings, the end wall 25 is provided with a central opening 26, adapted to slidably accommodate the spring follower cap F. The side, top and bottom walls of the casing B are of such a length as to terminate closely adjacent the head or horn of the coupler A. As clearly shown in Figure 1, the top wall 100

24 of the casing B is upwardly flanged at the front end thereof, to provide an abutment surface for the vertical end face of the coupler horn.

3 The shock absorbing means, as shown, is of the spring type and is housed within the casing B. In addition to housing the spring shock absorbing means, the casing B also contains the spring follower C and encloses the shank 27 of the coupler A. As shown in the drawings, the coupler shank is flared laterally outwardly at the forward end portion, and the rear end portion is provided with a flat transverse abutment face 28, which bears 10 on the front follower C. At the forward end, the side walls 23 of the casing B are flared laterally outwardly also, so as to permit of a certain amount of lateral swinging movement of the coupler with respect to the casing B. At the forward end, the shank 27 15 of the coupler A is supported by a transversely arranged supporting block 29 resting on the bottom wall 24 of the casing B, and secured thereto in any suitable manner, the same being shown as having a dowel pin 20 entering hole in casing B.

The coupler A is anchored to the casing B by means of the transversely disposed coupler key D, which extends through a slot or opening 30 in the shank 27 of the coupler, and aligned slots or openings 31-31 in the side walls of the casing B. As shown in the drawings, the coupler key D is of such a length that the opposite ends thereof extend 25 through the slots 19 of the center sills. The slots 31 in the casing B are of such a length as to permit a slight inward movement of the key D with respect to the casing, and the opening 30 in the coupler is of slightly 30 greater length than the width of the key D so that the coupler may have slight lateral movement. As shown, the openings or slots 19 of the center sills 10 are of considerably greater length than the slots 31 of the casing B, thereby permitting relatively great movement 35 of the key D inwardly of the car. As shown in the drawings which illustrate the normal release position of the shock absorbing mechanism, the coupler key D abuts the front end walls of the slots 31 of the casing B and the key D is slightly spaced from the front end walls of the slots 19 of the sills. It will be noted that a relatively short movement 40 of the key D is thus permitted during a draft action, and a much longer movement during the buffing action of the mechanism. Although the amount of movement in buff and draft may be varied within wide limits, the movement permitted of the key D in draft 45 is preferably one inch, and that permitted in buff in preferably six inches.

The spring resistance H of the shock absorbing mechanism is preferably composed of two coils, an inner light coil and a relatively heavier outer coil. The opposite ends

of the coils of the spring resistance H co-operate relatively with the spring follower cap F and front follower C. The spring follower cap F, as shown, is provided with an annular flange 32 at the forward end thereof, which co-operates with the end wall 25 of the casing B to positively limit outward movement of the spring follower cap with respect to the casing. The cap F is also provided with a forwardly projecting central hollow boss, which extends into the inner coil of the spring resistance and serves to center the same. As shown, the rear end of the inner coil of the spring resistance is disposed between the hollow boss and the outer wall of the cap F and bears directly on the rear end wall 33 of the cap. As shown, in the normal position of the parts the end wall 33 of the cap directly abuts the bolster stop casting 18.

The front follower C is interposed between the inner end of the shank of the coupler A and the spring resistance H. As shown, the front follower C comprises a main body portion in the form of a heavy rectangular plate, the plate-like body portion being provided with top and bottom forwardly extending arms 34-34, adapted to receive the top and bottom keys E-E. As shown, the arms 34 embrace the inner end of the shank of the coupler A but are slightly spaced therefrom so as to permit a certain amount of lateral play of the shank of the coupler with respect to the arms of the front follower. In addition to being spaced from the shank of the coupler A, the opposed inner faces of the arms 34 preferably diverge outwardly so as to permit the necessary angular movement of the shank of the coupler.

The top and bottom keys E serve to limit the movement of the front follower B outwardly of the mechanism. As clearly illustrated in Figures 1 and 2, the keys E extend through aligned openings 35-35 in the arms 34, and closely fit these openings so that there will be no relative movement between the keys and the front follower C. The casing B is also provided with aligned top and bottom slots 36 through which the keys E extend, the slots 36 being of such a length as to permit a limited amount of outward movement of the casing B with respect to the keys E and the spring follower C, the slots 36 preferably being of such a length as to permit the inner end walls of the same 110 to engage the keys E at the same time that the key D engages the front end walls of the slots 19 of the center sills. The outer ends of the keys E work in the longitudinal slots 20 of the center sills and normally abut the front end walls of these slots so that outward movement of the keys and the front follower will be prevented. The lengths of the slots 20 are such that full inward movement of the keys E is permitted during the 125

compression stroke of the mechanism. The keys E are preferably spaced apart vertically a distance substantially equal to the height of the shank of the coupler so that they will act as means to center the coupler axially with the shock absorbing mechanism and hold the same against tilting in a vertical plane with respect to the casing B.

The parts of the shock absorbing mechanism are held assembled and of overall uniform length by the retainer bolt G, which has the head thereof anchored in an opening 37 of the front follower C and has the head thereof disposed within the hollow boss of the spring follower cap F. The parts are so proportioned that the retainer bolt preferably maintains the spring resistance under an initial compression in the full release position of the mechanism.

In the normal position of the parts, the head or horn of the coupler A is slightly spaced from the abutment flange at the forward end of the casing B, the spacing being preferably equal to the distance of inward movement permitted between the key D and the casing B, so that the horn of the coupler will positively engage the front end of the casing when the key D engages the inner end walls of the openings 31 in the side walls 30 of the casing.

The operation of my improved railway draft rigging, and especially the shock absorbing mechanism thereof, assuming an inward or buffing action being applied to the coupler, is as follows: The coupler A will be forced inwardly, forcing the follower B inwardly against the resistance of the springs H. During the initial inward movement of the coupler, after the clearance between the front end wall of the coupler key slot and the key is taken up, the key D will be carried inwardly with respect to the casing B, until the same engages the rear end walls of the slots 31, whereupon the casing will be forced inwardly in unison with the coupler A. It will be evident that the coupler horn engages the outer end of the casing B at the same time that the key D engages the inner end walls of the slots 31, whereby the force is transmitted directly from the coupler horn to the front end of the casing B. The compression of the mechanism in buff will continue until the actuating force is reduced or the rear end wall 25 of the casing B comes into abutment with the bolster stop casting 18. The length of the slots 19 and 20 of the center sills is such that the full inward movement of the casing B, as described, is permitted before the keys engage the inner end walls of these slots. During release of the mechanism, upon the actuating force being reduced, the spring resistance H will force the front follower C outwardly, thus forcing the coupler A outwardly, carrying the key D therewith, and the latter, upon engage-

ment with the front end walls of the slots 31 of the casing B, will carry the casing B forwardly also. The force of the spring resistance H will also act through the front follower C and the keys E to restore the casing B to the normal position. Outward movement of the front follower C will be positively limited by engagement of the keys E with the front end walls of the slots 20 in the center sills, and outward movement of the casing B will, in turn, be limited by engagement with the flange 32 of the spring follower cap F which is resisted in its outward movement by the spring H interposed between the same and the front follower C.

Upon a pulling or draft action being applied to the coupler A, the coupler key D, which is secured to the shank of the coupler A, will be carried outwardly in unison with the coupler, and by engagement with the front end walls of the openings 31 in the casing B the casing B will be compelled to move outwardly in unison with the coupler, thereby pulling the spring follower cap F forwardly and compressing the spring resistance H between the spring follower cap and the front follower C, the latter being held in fixed position by the keys E which engage the front abutment walls of the openings 20 of the center sills. Outward movement of the casing B and compression of the spring resistance H will be arrested by the key D engaging the front end walls of the openings 19 of the center sills. In this connection it is pointed out that the slots or openings 36, in which the keys E work, are of such a length as to permit the necessary forward movement of the casing B during the described draft action.

From the preceding description, taken in connection with the drawings, it will be evident that I have provided an exceedingly simple and efficient construction of shock absorbing mechanism, wherein a relatively long stroke of the shock absorbing means is permitted, with consequent relatively long movement of the coupler member, wherein an exceptionally substantial support is provided for the coupler to prevent tilting or swinging movement of the same, thereby assuring the proper axial alignment of the coupler shank and the co-operating part of the shock absorbing mechanism, in this instance the front follower. In other words, by the arrangement shown and described, the danger of eccentric action between the butt end of the coupler shank and the front follower is positively eliminated. It is further pointed out that inasmuch as the coupler shank is confined between the two horizontally disposed keys E at the rear end thereof, and is secured to the casing B intermediate its ends by the transverse key D, and is further supported adjacent the head end thereof by the block 29, relative movement of the coupler

and the casing B in a vertical direction is positively prevented, although the necessary slight lateral movement is permitted. Inasmuch as the coupler is thus positively supported against vertical movement with respect to the casing B and, in fact, forms a part of said casing, the coupler head is overbalanced to a great extent by the casing B and the parts contained therewith, and 10 inasmuch as the casing B is supported by the saddle plate 21 at the rear end thereof, rocking of the casing B on the support 22 of the buffer block is prevented, thereby eliminating the excessive wear of the support, which is 15 a frequent occurrence in draft riggings of the ordinary construction.

While I have herein shown and described what I consider the preferred manner of carrying out the invention, the same is merely 20 illustrative, and I contemplate all changes and modifications which come within the scope of the claims appended hereto.

I claim:

1. In a railway draft rigging for cars provided with center sills, the combination with 25 shock absorbing means disposed between said sills; of a coupler; means for connecting said coupler with the shock absorbing mechanism and supporting the same, said means including a yoke member and an anchoring element extending through the yoke and also through the coupler shank between the ends thereof, and held against vertical displacement by engagement with the sills, said element being 30 movable with the coupler shank and effecting movement of the yoke in unison with the coupler in draft, said yoke having means at the front end thereof for supporting the coupler shank closely adjacent the coupler 35 head; and additional means extending through the sills and held against vertical displacement, said last named means embracing the inner end of the coupler shank and holding the same against vertical displacement in 40 all operative positions thereof.

2. In a railway draft rigging for railway cars having center sills, the combination with 45 a tubular member disposed between said sills; of a shock absorbing mechanism within said tubular member; a coupler having the shank thereof telescoped within said tubular member, the outer free end of said tubular member terminating adjacent the coupler head; means on said tubular member for supporting 50 the coupler shank at a point closely adjacent the head; a member extending through the coupler shank in back of the head and supported for movement in a direction longitudinally of the sills and held against vertical 55 displacement with respect to the sills, said member holding the coupler shank against vertical displacement, the coupler shank having the inner end thereof co-operating with the shock absorbing mechanism; and means 60 extending through said tubular member

above and below the coupler shank, embracing the inner end of said shank and holding the same against vertical displacement, said last named means having longitudinal movement with respect to the sills but held against vertical movement with respect thereto. 70

3. In a railway draft rigging for cars provided with center sills, the combination with a movable housing disposed between said sills; of a coupler having the shank thereof telescoped within said housing; a key for anchoring the coupler shank to the housing, said key extending through aligned openings in the coupler shank, the side walls of the housing and the center sills, said key being held against vertical displacement with respect to the members through which it extends by the top and bottom walls of said openings; shock absorbing means disposed within the housing, follower means engaging the shock absorbing mechanism, said follower means abutting the inner end of the coupler; transversely disposed top and bottom keys for anchoring the follower means to the housing, said keys having limited movement with respect to the housing and the center sills, and embracing the inner end of the coupler to prevent vertical displacement thereof; and a supporting element at the front end of the housing for the shank of the coupler, said supporting element being disposed closely adjacent the head of the coupler. 85

4. In a railway draft rigging for cars provided with center sills, the combination with 90 a tubular yoke element disposed between said sills; of a follower cap at the inner end of said yoke element and having limited movement with respect thereto and co-operating with stop means of the draft rigging; a coupler having the shank thereof telescoped within the tubular yoke means; a key extending through the shank of the coupler intermediate the ends thereof and supported for movement by said yoke means and sills; a front follower disposed within said yoke means and 95 abutting the inner end of the coupler, said front follower being held against outward movement with respect to the car proper; and a spring resistance interposed between the front follower and the follower at the rear 100 end of the yoke means. 110

5. In a railway draft rigging for cars provided with spaced center sills, the combination with an elongated housing having a spring follower cap at the rear end thereof, 115 co-operating with stop means fixed with respect to the car, said spring follower cap having its movement limited outwardly of the housing; a front spring follower disposed within the housing; a spring resistance interposed between said front follower and spring follower cap; a coupler having a shank extending into the housing and engaging the front follower; means for limiting outward movement of the front follower, said means 120 125 130

- comprising top and bottom keys fixed with respect to the front follower and working in slots in the housing and center sills, and being held against vertical displacement by said slots, said keys co-operating with the inner end of the coupler shank to prevent displacement thereof in a vertical direction; and means for connecting the shank of the coupler to the housing and supporting the shank in axial alignment with the shock absorbing mechanism, including a support on the housing adjacent the head of the coupler and a key extending through the shank of the coupler between the ends thereof and through aligned slots in the housing walls and center sills, said slots preventing vertical displacement of the coupler key and coupler while permitting longitudinal movement thereof with respect to the housing and center sills. 10
6. In a railway draft rigging for cars provided with spaced center sills, the combination with yoke means disposed between said center sills; of a coupler; shock absorbing means within the yoke, adapted to be actuated by said coupler; means on said yoke for supporting the outer portion of the coupler shank closely adjacent the coupler head; follower means at the inner end of the yoke, co-operating with said shock absorbing mechanism and engaging fixed stop means on the car; means for anchoring the coupler to the yoke for movement in unison during draft and permitting inward movement of the coupler with respect to the yoke and the shock absorbing mechanism during buff, to a limited extent, said anchoring means also anchoring the coupler to the center sills, the connection between the center sills and the anchoring means permitting relatively short outward, and greater inward, movement of the coupler; and anchoring means for limiting the outward movement of the shock absorbing mechanism, but permitting inward movement thereof. 20
7. In a railway draft rigging for cars having spaced center sills, the combination with yoke means disposed between the sills; of a coupler connected to the yoke for movement in unison during draft and having limited movement inwardly of the yoke during buff, shock absorbing means within the yoke, said yoke having means thereon for supporting the outer end portion of the portion of the coupler shank closely adjacent the coupler head; a follower engaged by the shank of the coupler and co-operating with the shock absorbing means; keys extending through openings in the yoke and center sills and embracing and guiding the inner end of the coupler shank in all operative positions thereof, said keys being held against outward movement by engagement with the front end walls of the openings in the sills and holding said follower against outward movement, the openings for said keys in the 30
- yoke permitting limited outward movement of the yoke with respect to said keys. 8. In a shock absorbing mechanism, the combination with a coupler; of a yoke member operatively connected to the coupler for movement therewith in draft, said yoke member being in the form of a casing; of front follower means disposed within the casing, said follower means being engaged and operated by said coupler in buff; a spring cap at the inner end of the casing, having limited movement lengthwise thereof and adapted to co-operate with fixed stop means of a car; and a spring resistance interposed between said spring follower cap and the front follower. 35
- In witness that I claim the foregoing I have hereunto subscribed my name this 20th day of December, 1927.
